UNITED STATES PATENT OFFICE

CLARENCE WARNER AND HARRY G. FISHER, OF DAYTON, OHIO, ASSIGNORS TO DELCO-LIGHT COMPANY, OF DAYTON, OHIO, A CORPORATION OF DELAWARE

PUMP

Application filed October 25, 1926. Serial No. 143,822.

This invention relates to improvements in a pumping device and particularly to that type of pumping device which includes a pump operatively connected with a pump operating mechanism, said pump operating mechanism being driven by a power device by means of a belt.

It is among the objects of the present invention to simplify the mounting of the pump, its operating mechanism and the power device, so that the pump and its operating mechanism are rigidly secured in proper relation. The power device is so mounted that it may be adjusted to vary the tension of the belt connecting it with the pump operating mechanism, while maintaining the alignment between these two elements. A further object is to provide the pump operating mechanism with an improved lubricating device which will provide lubricant in proper amounts to the moving elements thereof.

Further objects and advantages of the present invention will be apparent from the following description, reference being had to the accompanying drawings, wherein a preferred form of embodiment of the present invention is clearly shown.

In the drawings:

Fig. 1 is a side elevation of the pumping device assembly.

Fig. 2 is an end view of the pumping device showing the method of mounting the power device on the support. Other elements of the pumping device are omitted for the sake of clearness.

Fig. 3 is a fragmentary detail view of the power device mounting.

Fig. 4 is an end view of the pumping device taken from the pump operating mechanism end of the support. Certain members of the device have been omitted in the view for the sake of clearness.

Fig. 5 is a longitudinal section of the pump operating mechanism.

Fig. 6 is a fragmentary plan view of the mechanism shown in Fig. 5.

Fig. 7 is a detailed, perspective view of the oil throwing plate in the pump operating mechanism.

Referring to the drawings and more particularly to Fig. 1 the numeral 20 designates a pump having a cylinder 21 from which extends a pump rod 22. The pump has a flange 23 to which is secured the water tank 24. The cylinder 21 has a plurality of feet 25 extending from each side thereof, and adjacent these feet the cylinder housing has a lug 55 providing two parallel sides for purposes to be described.

The numeral 30 designates the pump operating device which is more clearly shown in the Figs. 4 and 5. Referring to these figures the numeral 31 designates the housing provided with a crankcase portion 32 having an opening 33 in which there is provided a removable cover 34. On the lower outside of the housing there are provided two lugs 35 and 36, the outer surfaces of which are parallel and spaced the same distance as the parallel sides of the cylinder housing 31 of the pump. At the end of housing 31, opposite opening 33, there is provided another opening 37 of lesser size however than the opening 33. In this opening 37 there is provided a cover 38 having a packing gland 39 associated therewith.

Inside the housing 31 there is provided a cylinder 40 coaxial with the opening 37. Above the cylinder 40 and within the housing 31 there is located a pocket 41 which communicates with the inside of the cylinder by means of aperture 42. An upwardly sloping shelf 43 formed on the end of the cylinder and extending across the housing provides an entrance to this pocket in close proximity to the path of travel of an oil thrower to be described hereinafter.

Within the cylinder 40 there is provided a piston 44 being connected with one end of the connecting rod 45 by means of wrist pin 46. As shown in Figs. 1 and 5 the rod 22 extends from the pump, through the packing gland 39 of the pump operating member, and has its screw-threaded end secured to the head of the piston 44. Intermediate the pump and the pump operating members the rod 22 has a disc portion 22a, adapted to be gripped by the tool for screwing the rod into the piston 44. On one side of the housing 31 there

60

65

70

75

80

85

90

95

100

is provided an extension 48 in which there is fitted a bearing 49 for supporting the drive shaft 50. On the outside end of this shaft there is secured a pulley 51 adapted to receive the belt 52. On the opposite end of this shaft and inside the housing 31 there is secured an eccentric 53 which is operatively connected to the strap portion 54 of the connecting rod 45.

16 Attached to one side of the eccentric is a fan-shaped plate 55 having a plurality of angular extensions 56. This plate is detailedly shown in Fig. 7 and is of such a conformation and so mounted on the eccentric that as 15 the eccentric rotates the extensions 56 will dip into the lubricating oil in the crankcase 32 and due to centrifugal force the oil, adhering to said extensions, will be precipitated through the entrance into the pocket 41.

20 Within the housing 31 there is provided a dished shelf 60, adjacent the eccentric so that the extensions 56 of the plate 55 will move in close proximity to the said dished shelf as the eccentric rotates. The dished 25 shelf has a passageway 61 communicating therewith which leads to an aperture 62 communicating in turn with the bearing 49 of shaft 50. In Fig. 6 it may be seen that the pocket 41, adapted to receive lubricant and 30 deliver the same to the cylinder 40 and piston 44, is in direct alignment with and in the plane of operation of the eccentric 53. It may also be seen that the dished shelf 60 lies by the side of the disc 55 carried by the eccentric 53.

When the pump operating device included in the housing 31 is operated by the rotation of the pulley 51 the shaft 50 will be rotated thus causing the eccentric 53 to reciprocate 40 the piston 44 in the cylinder 40, consequently causing reciprocation in pump rod 22. Rotation of eccentric 53 will cause the extensions 56 of plate 55 to dip into the oil and pick up a certain amount thereof, and, due to centrifugal force the oil will be thrown straight 45 forward into the pocket 41 to lubricate the piston and cylinder and due to the formation of the angular extension 56 the oil will be thrown sidewise against the wall of the 50 crankcase and then the oil will flow down said wall into the dished shelf 60 from whence it will flow through passageway 61 and aperture 62 to lubricate the shaft 50. The pocket 41 and the dished shelf 60 will consequently 55 receive an oil supply directly from the oil throwing plate 55.

As has been mentioned before, the pump and the pump operating mechanism include parallel sides on the outside of their casings. 60 To these sides are attached angle irons 70 and 71 which form a support for the entire pump assembly including the power device. At the pump operating mechanism end of the angle irons 70 and 71 there is provided a foot 65 72 which engages the outside of the vertical

arm of the angle irons. Through-bolts 73 extend through the foot, angle irons and the lugs formed on the pump operating mechanism housing, thus securing the angle irons to the housing and due to the parallel surfaces with which the angle irons engage, they also will be held parallel. The pump is likewise anchored between the angle irons by means of through-bolts 74 and 75. The through-bolts 75 which hold the pump and angle irons together also secure the one end of the foot 76 to the angle irons. The opposite end of the foot 76 is secured to the angle iron by means of the short bolts 77 provided in each angle iron. The purpose of this will be described 80 hereinafter.

As shown in Fig. 1 the angle irons 70 and 71 extend beyond the foot 76, and are held parallel due to the fact that they are secured to the parallel and equally spaced sides of the 85 pump and pump operating mechanism.

Referring to Figs. 2 and 3, the method of attaching the power device 80, shown in the form of an electric motor, is clearly illustrated. The electric motor is provided with the ordinary standard base 81 to which is attached a guide member 82 by means of studs 83. The ends of the guide member are upturned as at 84, the edges thereof engaging with the bottom of the base 81 of the motor. This guide member 82 is of a width equal to the distance between the parallel sides of the pump and thus said guide member slidably fits between the vertical arms of the angle irons. The sides of the guide member adjacent the angle irons are open and a clamping bolt 85 extends transversely therethrough thus permitting the guide member to be slipped back and forth between the angle irons for the purpose of adjusting the belt 52. The front end of the guide member is cut away to permit clearance for the head of bolts 77. The clamping bolt 85 has a head 87 engaging with the angle iron 71 while at the other end there is provided a nut 88 adapted to be screwed against the vertical angle iron 70 for simultaneously clamping the angle irons 70 and 71 and the guide member 82 together. By loosening this nut 88 the motor with its guide member 82 may be slid back and forth along the angle irons for the purpose of adjusting the tension of belt 52. By this structure adjustments may be made without effecting the alignment between the pulleys 51 and 86 of the pump driving mechanism and the motor respectively. After the guide member 82 is once secured in correct alignment on the motor base 81 it need not be removed even when it is desired to remove the motor from the angle irons for any purpose. Instead of providing the angle irons with feet 72 and 76, as shown in the drawings, they may be secured to any suitable support in any suitable manner. The object of providing the angle irons on each side of the 100

motor pump and pump operating mechanism is to hold these three members of the pumping device in operative alignment while making it possible to mount the pumping device 5 by the angle irons on any suitable support.

The tank 24 is suspended only on the flange 23 of the pump. A small lug or extension 90 is provided on the pump operating mechanism, normally in spaced relation with the 10 tank 24 to permit easy application of the tank to the flange 23, however, providing a support for said tank if any undue load be placed thereon which support would substantially prevent any strain on the flange 23.

15 While the form of embodiment of the present invention as herein disclosed, constitutes a preferred form, it is to be understood that other forms might be adopted, all coming within the scope of the claims which follow.

20 What is claimed is as follows:

1. In a pumping apparatus, the combination with a driving member and a driven member, of a support for said members including spaced parallel portions, means carried by one of said members for holding same in operating alignment with the other member but which permits said member to be slid longitudinally on said spaced parallel portions, and tie means connecting said spaced 25 portions for adjustably clamping said first named means between said spaced parallel portions.

2. In a pumping apparatus, the combination with a driving member and a driven member, of a support for said members including spaced parallel portions, means carried by one of said members for holding same in operating alignment with the other member but which permits said member to be slid 30 longitudinally on said spaced parallel portions, and means for drawing said supports toward said first named means for adjustably clamping same between said spaced parallel portions.

45 3. In a pumping apparatus, the combination with a driving member and a driven member, means drivingly connecting said members, of a support for said members including spaced parallel angle irons, and mounting means for said spaced parallel angle irons, a guide member carried by one of said members, said guide member extending between said angle irons and cooperating therewith for holding said member in operative alignment with the other member, while permitting said member to be slid longitudinally on said angle irons, and means for drawing said spaced parallel angle irons toward said guide member for adjustably clamping same between said spaced parallel angle irons.

55 4. In a pumping apparatus, the combination with a driving member and a driven member, means drivingly connecting said members, said driven member having a por-

tion provided with spaced parallel sides, angle irons secured to said parallel sides whereby a portion of the angle irons will be maintained in spaced parallel relation, a guide member carried by said driving member, said guide member extending between another portion of said angle irons and cooperating therewith for holding said driving member in operative alignment with the driven member, while permitting said member to be slid longitudinally on said angle irons, and means for drawing the second named portion of said angle irons toward the guide member for adjustably clamping same between said angle irons.

5. In a pumping apparatus, the combination with a pump, a pump operating member and a driving member, of a support for said members and said pump including spaced parallel portions, means carried by one of said members for holding same in operating alignment with the other member but which permits said member to be slid longitudinally on said spaced parallel portions, and tie means connecting said spaced portions for adjustably clamping said first named means between said spaced parallel portions.

6. In a pumping apparatus, the combination with a pump, a pump operating member and a driving member, of a support for said members and said pump including spaced parallel portions, means carried by one of said members for holding same in operating alignment with the other member but which permits said member to be slid longitudinally on said spaced parallel portions, and means for drawing said supports toward said first named means for adjustably clamping same between said spaced parallel portions.

7. In a pumping apparatus, the combination with a pump, a pump operating member and a driving member, of means drivingly connecting said members, of a support for said members and said pump including spaced parallel angle irons, and mounting means for said spaced parallel angle irons, a guide member carried by one of said members, said guide member extending between said angle irons and cooperating therewith for holding said member in operative alignment with the other member, while permitting said member to be slid longitudinally on said angle irons, and means for drawing said spaced parallel angle irons toward said guide member for adjustably clamping same between said spaced parallel angle irons.

8. In a pumping apparatus, the combination with a pump, a pump operating member and a driving member, of means drivingly connecting said members, said pump and pump operating member having portions provided with spaced parallel sides, angle irons secured to said parallel sides whereby a portion of the angle irons will be maintained in spaced parallel relation, a guide member

carried by said driving member, said guide member extending between another portion of said angle irons and cooperating therewith for holding said driving member in operative alignment with the pump operating member, while permitting said member to be slid longitudinally on said angle irons, and means for drawing the second named portion of said angle irons toward the guide member for adjustably clamping same between said angle irons.

9. In a pumping apparatus, the combination with a driving member and a driven member, of a support for said members including spaced parallel portions having bearing surfaces, means having longitudinal bearing surfaces carried by one of said members for holding same in operating alignment with the other member but which permits said member to be slid longitudinally on said spaced parallel portions, and tie means connecting said spaced portions for simultaneously adjustably clamping said surfaces together.

25 In testimony whereof we hereto affix our signatures.

CLARENCE WARNER.
HARRY G. FISHER.
